UNITED STATES PATENT OFFICE.

DOS TAYLOR, OF SHARPSBURG, PENNSYLVANIA, ASSIGNOR TO H. J. HEINZ COMPANY, OF PITTSBURG, PENNSYLVANIA, A CORPORATION OF PENNSYLVANIA.

DESIGN FOR A BOTTLE.

No. 39,625.

Specification for Design.

Patented Oct. 20, 1908.

Application filed June 5, 1908. Serial No. 437,030. Term of patent 14 years.

To all whom it may concern:

Be it known that I, Dos TAYLOR, a citizen of the United States, residing at Sharpsburg, in the county of Allegheny and State of Pennsylvania, have invented a new, original, and ornamental Design for Bottles, of which the following is a specification, reference being had to the accompanying drawing, forming part thereof.

The drawing shows in Figures 1, 2 and 3, the bottle in front and side elevation, and in bottom plan respectively.

I claim—

The ornamental design for a bottle as shown.

DOS TAYLOR.
